UNITED STATES PATENT OFFICE.

HENRY W. GRAVES, OF CHICAGO, ILLINOIS, ASSIGNOR OF ONE-FIFTH TO ALBERT SCHEIBLE, OF CHICAGO, ILLINOIS.

ROOF-TRUSS.

1,360,931.

Specification of Letters Patent. Patented Nov. 30, 1920.

Application filed January 23, 1920. Serial No. 353,602.

To all whom it may concern:

Be it known that I, HENRY W. GRAVES, citizen of the United States, residing at Chicago, Illinois, have invented certain new and useful Improvements in Roof-Trusses; and I do hereby declare the following to be a full, clear, and exact description of the invention, such as will enable others skilled in the art to which it appertains to make and use the same.

My invention relates to roof trusses, one of its general objects being that of providing a roof truss which will be unusually light, easy to manufacture, low in cost and easy to erect in proportion to its strength and rigidity. In another aspect, my invention aims to provide a roof truss for an arched roof, involving relatively few compression members, and so designed as to impose relatively light strains on the tension members. In a further aspect, my invention aims to provide an arched roof truss arranged for automatically distributing unbalanced loads from one lateral half of the truss to the other half by applying strains equivalent to what would constitute a balancing load; for which purpose, my invention aims to provide a truss divided medially into two halves by a compression member affording pivot means about which the top chord may rock; and by providing separate bracing for each of the truss halves to resist a distortion of the top chord portion thereof. Furthermore, my invention aims to provide the bracing for each truss half in such a manner as to obviate the need of either vertical or oblique struts. Still further objects of my invention will be apparent from the following specification and from the accompanying drawings, in which drawings.

Figure 1 is an elevation of a truss embodying my invention.

Figs. 2, 3 and 4 are enlarged sections taken along the correspondingly numbered lines in Fig. 1.

Fig. 5 is a diagrammatic view of another truss embodying my invention and having a larger number of tension members than the truss of Fig. 1.

Referring to the embodiments of the drawings, I accomplish the purposes of my invention in four ways:

First, by employing only two members having the stiffness required for resisting

compression, namely an arched upper chord and a single vertical strut connecting the center points of the upper and lower chords of the truss.

Second, by employing tension members radiating respectively from the juncture of the strut with the bottom chord and from the ends or heels of the truss, which tension members all are connected at their other ends to the top chord and are each disposed entirely within one lateral half of the truss;

Third, by including among these tension members elements arranged in pairs, with the members of each pair respectively connecting a single point of the top chord with the center of the bottom chord and one end of the bottom chord;

And fourth, by employing a parabolic shape for the top chord and so spacing the points at which the pairs of tension members are connected to the top chord that these points will be equally spaced in a direction parallel to the bottom chord.

For example, in the diagrammatic embodiment of Fig. 5, the top chord 1 is in the form of a parabola having its principal axis vertical, and this axis coincides with the medial line of a strut 2 which connects the middle of the top chord 1 with the middle point of the bottom chord 3. Of these members, both the top chord and the strut are

of such angular section as to adapt them to resist compression strains, while the bottom chord is designed for resisting tension only. Radiating from the middle point A of the bottom chord (or from the juncture of the latter with the single strut 2) are

tension members 4 connected at their other ends to points on the top chord respectively disposed at right angles to equidistant points on the bottom chord, or on a line parallel to the latter as indicated in Fig. 5. These same points on the top chord in each lateral half of the truss are also connected by tension members 5 to the nearer end of the truss,

although such a tension member may be omitted between each end of the top chord and the nearest point from which the latter is connected to the center point of the bottom chord. That is to say, the tension members in each half of the truss are disposed in pairs (such as the members 4^a and 5 in Fig. 1), with the members of each pair connecting a single point on the top chord with the opposite ends of the corresponding

half of the bottom chord; although the companion member to the lowest radial tension element 4^b may be omitted in practice, as it would substantially coincide with one 5 end portion of the top chord, and this portion of the top chord is ample in practice to resist the tension strains which would fall upon a corresponding tension member.

With the truss thus arranged, the parabolic form of the top chord automatically distributes the strains due to a load distributed uniformly over the top chord, so 10 that no intermediary members whatever would be required for coöperating with the bottom chord 3 in maintaining the rigidity of the truss. If the load is unevenly distributed, as for example by being applied only on some portion of the left-hand half of the top chord in Fig. 5, this load would 15 tend to cause a downward deflection or flattening of the left-hand half of the top chord, thereby tending to rock this top chord about its medial point C and correspondingly tending to cause an upward bulging 20 or greater convexing of the right-hand half of the top chord. However, any such upward bulging tendency will be resisted by the tension members 4 in the right hand half of the truss, and the vertical components 25 of the tension due to the resulting strains on these normally unloaded tension members will produce an upwardly directed stress on the strut 11, thereby placing the members 5^c and 5^d under tension. Likewise, 30 the upward bulging tendency of the right-hand half of the top chord will place the members 5 and 5^d under tension, so that the members 4 and 5 in the right-hand half of the truss will all exert downward strains on 35 the top chord having a joint effect equivalent to that of placing a balancing load on the right-hand half of the top chord.

Moreover, since the top chord is parabolic in shape and since the tension members lead 40 from the end of the right-hand half of the bottom chord to points so spaced along the top chord as to correspond in spacing to equal strain distributions in a parabolic chord (namely to points at right angles to 45 equidistant points on the bottom chord) there will be no resulting strains requiring either vertical or oblique auxiliary struts to resist the same. I am therefore able to take care of the strains due to an uneven 50 load distribution on the roof without employing any struts other than the strut 2, which strut divides the truss into two halves and which rigidly spaces the center points of the top and bottom chords so as to afford 55 a leverage about which an unbalanced load on one-half of the truss can rock the top chord to cause the tension members in the other half of the truss to exert the required balancing and truss-stiffening strains.

60 By thus eliminating all struts other than

the medial vertical member of the truss, I am able to reduce the weight and cost of the truss considerably over that required for the types of roof trusses heretofore in use. Moreover, since the tension members of my 70 truss are normally unloaded (owing to the parabolic form of the top chord, the mathematically proportioned spacing of the connecting points on each half of the top chord, and the arrangement of these tension members in pairs), I can employ tension members of relatively light weight and cost. Furthermore, since each of the tension members is disposed entirely in one lateral half 75 of the truss, I not only greatly reduce the weight of these members over that required in trusses employing tension members reaching from one lateral half of a truss into the other, but also greatly reduce the strains on such members due to unbalanced load effects on the top chord. Consequently, I can further decrease the cross-sectional size and cost of these tension members as compared with those required for trusses in which the tension members are not each confined 80 to a single lateral half of the truss.

While various elements of the truss are connected to one another theoretically at the same points, it will be understood that in practice some of these connections may be 90 made through gusset plates or the like as intermediaries; and it will also be obvious that the cross-sectional shapes of different members of my truss may conform to common practice in truss construction. For example, 100 in the truss of Fig. 1, the top chord is bent from a pair of steel angles 6 bolted to each other at their centers through gusset plates 7 and at their ends through heel plates 8, which heel plates also afford the connections 105 between the two ends of the top chord and the bottom chord. This bottom chord is here shown as a single angle bar 9, and has another gusset plate 10 riveted to its middle.

The gusset plates 7 and 10 also form the 110 connections from the top and bottom chords to the vertical strut which forms the medial compression member of the truss and which is here shown as consisting of two angle bars 11 riveted to opposite sides of the gusset 115 plates 7 and 10. The latter plate also forms the means of connecting the tension members 4 to the center point of the bottom chord; that is to say, the lower ends of these tension members 4 are all riveted to the gusset 120 plate 10 at such points that the members 4 radiate from the middle point A in the angle bar forming the lower chord. The upper ends of the tension members 4 and of the companion tension members 5 are here 125 shown as interposed between the two angle bars 6 forming the top chord and as jointly riveted to these angle bars, after the manner of Fig. 3, thus affording single connections between the top chord and the pairs of 130

associated tension members. However, at the center of the truss, the longest tension members 5^e and 5^f desirably are riveted to the upper gusset plate 7 in such a manner as 5 to aline them with the center C of the top chord, which center is also in alinement with the axis of the strut 11, thereby affording the properly alined connection through which the upward vertical component of the 10 tension on all of the members 4 is transmitted by the strut 11 to the longest tension members 5^e and 5^f.

While the truss illustrated in Fig. 1 only has tension members radiating from the 15 point A to two points in each half of the top chord, it will be obvious that the number of such connected points may be varied in accordance with the relative height and spread of the trusses and with the loads for 20 which the latter is designed. However, the shortest tension members 5^a may be omitted in practice, as being too nearly coincident with the adjacent end portions of the top chord. Furthermore, while I have complied 25 with the statutes by illustrating and describing the truss of my invention in a desirably commercial embodiment, I do not wish to be limited to the details of the construction and arrangement thus disclosed, 30 nor to the use of the mentioned materials, it being obvious that the same might be modified in many ways without departing from the spirit of my invention as disclosed in the appended claims. Neither do I wish 35 to be limited to an exact conforming of the arch member of my truss to a parabolic curve, since this can only be approximated in the practical construction of such trusses.

It will be noted from Fig. 5 that the 40 bracing of the arch is effected entirely by web members forming triangles connected at their apices to the arch and each having half of the main chord as its base. (In this aspect, the central strut 2 forms a side of 45 two of the triangles). The bracing is therefore quite simple, and by employing a parabolic arch with the connections to it spaced as described, I reduce the strains on the webs so that these can be unusually light in 50 proportion to the size of the arch and the load for which the latter is designed. By making these connections to the arch at an odd number of points, I can readily use the medial web as a means for distributing an 55 unbalanced load from one half of the arch to the other, while the radial disposition of part of the tension members prevents an undue bulging or deflecting of the arch with such an uneven load distribution.

60 Moreover, I do not wish to be limited to the employment of the structure of my invention as a roof truss, since it could obviously be used with equal facility as a bridge truss or as a girder for other purposes.

I claim as my invention:

1. A roof truss comprising an arch, a main chord for the same, a pair of secondary chords respectively spanning half of the arch, a strut disposed medially of the 70 truss and connecting the arch with the main chord, and bracing means associated with each half of the truss for resisting an increased convexing of one-half of the arch by an excessive loading of the other half 75 thereof.

2. A roof truss as per claim 1, in which the bracing means for each truss half consists entirely of tension members connecting the ends of the bottom chord portion of 80 that truss half with points on the top chord portion of the same truss half, which points are respectively at right angles to the bottom chord opposite equidistant points on the latter.

85 3. A roof truss as per claim 1, in which the bracing means for each truss half consists entirely of tension members disposed oblique to the bottom chord and connecting the top chord portion of the same truss half 90 with the ends of the bottom chord portion of the same truss half.

4. A roof truss comprising a top chord curved in the form of a parabola, a bottom chord disposed at right angles to the axis 95 of the parabola, a strut connecting the center of the top member and the bottom chord and tension members arranged in pairs, the members of each pair connecting the same point on the top chord respectively with the 100 lower end of the strut and the nearer heel of the truss.

5. A roof truss comprising a substantially parabolic compression top chord, a bottom chord at right angles to the axis of the parabola defined by the top chord, members connecting the center of the top chord respectively with the center and the two ends of the bottom chord, and other members arranged in pairs with the members of each 110 pair connecting the same point of the top chord respectively with the center of the bottom chord and the nearer end of the latter.

105 6. A roof truss comprising a substantially parabolic compression top chord, a bottom chord at right angles to the axis of the parabola defined by the top chord, a strut connecting the centers of the top and bottom chords, tension members connecting the center of the top chord respectively with the ends of the bottom chord, and other tension members each disposed entirely in one lateral half of the truss; the said other tension members all connecting points on the top chord with ends of that half of the bottom chord which is opposite the said points.

115 7. A roof truss comprising a substantially parabolic compression top chord, a bottom 120

- chord at right angles to the axis of the parabola defined by the top chord, a strut connecting the centers of the top and bottom chords, tension members connecting the center of the top chord respectively with the ends of the bottom chord, and other tension members each disposed entirely in one lateral half of the truss; the said other tension members all connecting points on the top chord with ends of that half of the bottom chord which is opposite the said points and including pairs of members respectively connecting the same points of the top chord with the nearer half-bottom-chord ends.
- 5 11. A truss structure comprising a parabolic arch, and web members radiating from the ends of the arch and from a point axial thereof, the said web members being connected in pairs to each other and to the arch at an odd number of points on the latter consecutively spaced uniformly from each other and from the ends of the arch in a direction at right angles to the axis of the arch. 40
- 10 12. A truss structure comprising a parabolic arch, and web members radiating from the ends of the arch and from a point axial thereof; the said web members being connected in pairs to each other and to the arch at an odd number of points on the latter consecutively spaced uniformly from each other and from the ends of the arch in a direction at right angles to the axis of the arch. 45
- 15 13. A truss structure including a parabolic arch, a main chord for the same, web members connecting the middle of the chord with various points on the arch, and web members respectively connecting the same points with the nearer end of the chord. 50
- 20 14. A truss structure comprising a substantially parabolic arch, and web members arranged in pairs all connecting a single point axial of the arch with the ends of the arch, the members of each pair being substantially jointly connected to each other and to the arch. 55
- 25 15. A truss structure comprising a parabolic arch, a main chord at right angles to the axis thereof, webs connecting the middle of the chord with points on the arch consecutively spaced uniformly from each other and from the ends of the arch in a direction parallel to the chord, and webs connecting each of the same points with the nearer end of the chord. 60
- 30 16. A truss structure comprising an arch, a main chord, and auxiliary bracing members consisting entirely of web members forming a plurality of triangles connected at their apices to the arch and each having half of the main chord as its base. 65
- 35 17. A truss structure comprising an arch, a main chord, and auxiliary bracing members consisting entirely of web members forming a plurality of triangles connected at their apices to the arch and each having half of the main chord as its base. 70
